TOOL-ORIENTING METHOD AND APPARATUS

George A. Smith, Philadelphia, Pa., assignor to
Sperry-Sun Well Surveying Company, Philadelphia, Pa., a corporation of Delaware

Application November 1, 1940, Serial No. 363,849

Application November 1, 1940, Serial No. 3,633,613

8 Claims. (Cl. 255—1.6)

This invention relates to means for orienting a tool in a bore hole by manipulation of a drill stem supporting the tool.

In the setting of tools such as whipstocks or other directional drilling tools in bore holes, the tools are generally lowered into the hole by means of a sectional drill stem and then, through some means indicative of the position of the tool, the position of the tool first attained is determined by means of an inclinometer or other well surveying instrument. From this a determination is made of the amount of rotation of the drill stem necessary to bring the tool into desired position, and such rotation is imparted to the drill stem. However, since, by reason of friction, a given rotation of the drill stem at the surface may not result in a corresponding rotation of the tool in the bottom of the hole, a further check is generally necessary in similar fashion to insure that after the first adjustment the tool has been positioned as desired. It will be clear that a number of manipulations are necessary to effect the ultimate positioning of the tool by these methods.

It has been proposed to effect the orientation of tools in sloping holes to provide the tool with means weighting it asymmetrically so that the tool, which is swivelled to the drill stem, will automatically turn to bring a predetermined part thereof to the low side of a hole. Such arrangements have been impractical, however, since friction will prevent free seeking of a tool by the low side of the hole even when the hole is very considerably inclined with respect to the vertical. In slightly inclined holes, such a device is not only impractical, but wholly inoperative.

It is the broad object of the present invention to provide an apparatus for the automatic location of a tool in predetermined azimuthal position which is capable of securing proper positioning of the tool in any but a substantially precisely vertical hole. This result is effected by providing a pilot means which is extremely sensitive to inclination. Thereafter, by using the position of this pilot means as an index, relatively rotatable members are properly clutched together to effect predetermined simultaneous rotation thereof to bring the tool to proper position.

The broad object of the invention, as well as subsidiary objects primarily relating to details of construction, will become apparent from the following description, read in conjunction with the accompanying drawing, in which:

Figure 1 is a half section taken through the axis of a drill stem illustrating the parts cooperating in providing orientation of a tool; million

Figure 2 is a fragmentary enlarged section illustrating particularly the locking means;

Figure 3 is a fragmentary transverse section taken on the plane indicated at 3-3 in Figure 2;

Figure 4 is a similar section taken on the plane indicated at 4-4 in Figure 2.

A sectional hollow drill stem of conventional

construction has included in it adjacent its lower end a sub 2, which provides a support for various operating elements. Into the lower portion of this sub 2 there is threaded at 4 a box or coupling 6 to which may be secured a suitable bit. This box 6, together with a downwardly facing shoulder on the sub 2, provides a mounting for an annular ring member 8 to which is secured a whipstock 10 by means of a conventional shear pin 12. As the parts are thus initially associated, the bit will be located at the upper portion of the deflecting face of the whipstock. While a whipstock is herein illustrated as the tool to be oriented, it will be evident that the invention is equally applicable to the orientation of various other drilling tools of types known in the art.

The sub 2 and the member 8 define a race 14 between surfaces 16 and 18, on which there may freely move a steel ball 20. Defining the bottom of the race 14, the sub is provided with a shoulder 22 into which are milled a number of sockets 24, each having a cylindrical upper portion and a semi-spherical lower portion of a radius slightly larger than that of the ball 20. These sockets 24 are located about the entire circumference of the sub 2, and are arranged substantially in contact subject to the provision of a sufficient wall thickness, as illustrated, to withstand strains referred to hereafter.

The ring 8 is provided interiorly below the race 14 with an annular shoulder 26 of semi-circular axial section, and in this shoulder there is milled a single semi-spherical socket 28, which, taken opposite and in combination with one of the sockets 24, substantially defines a semi-spherical receptacle for the ball 20.

located between the sub 2 and the ring 8 is a ball supporting ring 30, which may be quite thin, since it is never under any substantial stress. Extending inwardly from this ring 30 is a pin 32, which engages a sleeve 34 axially movable in the bore in the sub 2 and normally urged upwardly by a strong spring 36 into engagement with an adjustable ring 35 threaded into the upper portion of the sub and adapted to adjust the uppermost position of the ring 30. The sleeve 34 is

provided with a go-devil seat indicated at 38, to which reference will be made later.

Packing 42, provided in the sub 2 and ring 8, engages the inner and outer surfaces of the ring 30. Other packing 43 is preferably located between the sub 2 and the upper portion of the ring 8, so as to effect isolation of the race 14 and the associated sockets from the mud inside and outside the sub.

In the use of this device, the elements are assembled as illustrated, the whipstock or other tool 10 being secured by the shear pin 12 to the ring 8 in a predetermined relationship to the socket 28. For example, this socket may be located directly above the shear pin, though, of course, any other definitely determined position can be used. The spring 36 now urges the sleeve 34 upwardly and with it the ring 30 to locate the upper end of that ring substantially at or slightly above the level of the shoulder 22. Thus it will be obvious that the ball 20 will engage only smooth annular walls at its sides and bottom so that it has a race within which it may freely move. This race should, of course, be clean, and to maintain it clean, it is desirable that it be filled in the assembly of the apparatus with a light oil. Thereafter as compression occurs as the apparatus is lowered within the mud, some mud will be forced by the packings 42 and 43, but if the packings are properly fitted, any solid material will be effectively filtered out and what enters the race will be clear liquid, which will offer no hindrance to the free movement of the ball 20.

The apparatus in this condition is lowered into the bore hole by the making up of the sections of the drill stem until the whipstock is located at substantially the level at which it is to be set. Desirably, the drill stem is then rotated through several revolutions in order to twist it to the extent that friction may ultimately dictate. The rotation is then stopped.

If the hole is now slightly off vertical (as is usually the case), the ball 20, freely moving in its race, will take a position at the low side of the hole because of its quite free movement. Such position will be taken even though the slope of the hole is very slight.

A go-devil is now dropped through the drill string to ultimately rest on the seat 38 and compress the spring 36, thus driving the sleeve 34 downwardly. The pin 32, moving downwardly in the slot 33 through which it extends, will move the sleeve 30 below the bottoms of the sockets 24 and 28. Assume now that the socket 28 is not on the low side of the hole. Under such conditions, the ball 20 will drop into that socket 24, which is most nearly aligned with it. However, it cannot drop completely to the bottom of the socket 24, but will drop partially into such socket until it rests on the annular shoulder 26 in the position 20'. The extent of movement is such as to bring the center of the ball below the shoulder 22, so that the application of rotary movement will not tend to cause the ball to jump from the socket 24 in which it is thus resting. In fact, the sockets 24 are desirably slightly inclined downwardly away from the direction of rotary movement, so that rotational forces will tend to move the ball 20 downwardly rather than upwardly.

It will now be evident that the ball 20 will still occupy substantially a position at the low side of the hole with an error less than half the angular spacing between sockets 24. Inasmuch

as there is no point in securing extreme accuracy of positioning of a whipstock, because the drilling always errs to some substantial extent in any event from precise correspondence with the whipstock position, the error in the marking of the low side of the sub is of no substantial consequence.

The drill stem is now rotated through at least one complete revolution, but preferably through several complete revolutions. As rotation now takes place, the ball 20 will move with the socket 24 in which it has dropped until it comes into alignment with the socket 28. As soon as this occurs, it will drop into the socket 28, now occupying the position 20" illustrated in Figure 2. The depth of the socket 28 is such as to bring the center of the ball substantially below the shoulder 26, so that there will be no tendency for it to jump out of socket 28. The rotation is, of course, desirably slowly effected, so that the ball will not overrun the socket 28, though even if it does so, if several revolutions of the drill stem are made, its dropping into the socket will be certain to be effected in one of them. The socket 28 is desirably sufficiently larger than the ball so as to provide its easy dropping thereinto.

As soon as the ball occupies the position within the socket 28, it will be evident that the sub 2 and the ring 8 are locked together. Thus the whipstock will be rotated with the sub, with the result that when the sub completes each revolution the position of the whipstock will be definitely known by reason of the fact that at the completion of each such revolution the socket 28 will be, subject to the slight error mentioned above, at the low side of the hole. From a previous survey the azimuth of the low side of the hole will be known and hence this low side of the hole forms a reference for azimuthal positions. If the whipstock, by reason of such positioning, is not in desired location, the drill stem is then given such further rotation as will serve to bring the whipstock into the predetermined desired azimuthal position. The weight of the drill stem may then be caused to bear on the shear pin 12 to shear it off, thereby driving the whipstock into the earth and so fixing it in position.

If a drill bit is carried at the lower end of the whipstock, drilling may then be immediately effected without further delay. In such case, of course, the go-devil is desirably provided with a mud passage, so that circulation may be provided through the bit. The ball 20 may be left in its position in the sockets, with the result that the ring 8 will rotate with the sub. However, since a broken portion of the shear pin may project and consequently during the drilling blows may be imparted to the ring 8, it may be desirable to remove the ball 20 from the sockets. This may be effected merely by raising the go-devil by means of a suitable catcher, whereupon the spring 36 will move the spring 30 upwardly to bring the ball 20 into the race 14. Thereafter the ring 8 will be free.

It will be evident from the above description that orientation of a tool may be effected without the necessity for use of any surveying instrument or the occurrence of the delay resulting from its use. At the same time, the tool orienting means is extremely sensitive to inclination. Of course, it is not reliable if the hole is so nearly vertical that a random inclination of the elements in the drill stem might throw the race 14 to an inclination not corresponding with that of the

hole. Since before any sidetracking is done the slope of the hole is always known, it can be readily determined as a preliminary matter whether this apparatus is proper for use.

It will be obvious that the orienting apparatus described may be used consistently with any other apparatus generally associated with directional drilling. For example, directly above the sub 2 there may be located a suitable retrieving apparatus such as disclosed in Kothny Patent 2,107,420. In fact, a single go-devil might be used for operating both pieces of apparatus, since they would function at quite different times.

Additionally, if desired, provision may be made for checking the whipstock position before it is released by the provision on the upper end of the whipstock of one or more magnets which produce magnetic fields through a non-magnetic sub located above the sub 2 and arranged to receive a surveying instrument in the manner described in Hyer Patent 2,120,670.

It will be evident that the pilot means, constituted herein by the ball 20, may take other forms, the pilot means not necessarily being the locking means between the drill stem and the tool to be oriented. Variations may be made without departing from the scope of the following claims.

What I claim and desire to protect by Letters Patent is:

1. In combination, a pair of relatively rotatable members adapted to be positioned in a bore hole, an element normally freely movable relatively to one of said members to occupy a position defining the low side thereof, means effecting fixing of said element to said member for rotation therewith, and cooperating means on the second member engageable with said element during rotation of the first mentioned member to effect rotation of the second member with the first.

2. In combination, a pair of relatively rotatable members adapted to be positioned in a bore hole, a circular race, a ball movable in said race relatively to one of said members to occupy a position defining the low side thereof, means effecting fixing of said ball to said member for rotation therewith, and cooperating means on the second member engageable with said ball during rotation of the first mentioned member to effect rotation of the second member with the first.

3. In combination, a pair of relatively rotatable members adapted to be positioned in a bore hole, a circular race, a ball movable in said race relatively to one of said members to occupy a position defining the low side thereof, means effecting fixing of said ball to said member for rotation therewith, comprising sockets in said member and means effecting location of the ball in one of said sockets, and cooperating means on the second member engageable with said ball during

rotation of the first mentioned member to effect rotation of the second member with the first.

4. In combination, a pair of relatively rotatable members adapted to be positioned in a bore hole, a circular race, a ball movable in said race relatively to one of said members to occupy a position defining the low side thereof, means effecting fixing of said ball to said member for rotation therewith, comprising sockets in said member and means effecting location of the ball in one of the sockets, and cooperating means on the second member comprising a socket for receiving said ball during rotation of the first mentioned member to effect rotation of the second member with the first.

5. In combination, a pair of relatively rotatable members adapted to be positioned in a bore hole, means for defining the low side of one of said members when that member is stationary in the bore hole and for thereafter defining that side during rotation of said member, and means for clutching said members together for simultaneous rotary movement when said defined low side of the first member occupies a predetermined angular relationship to the second member.

6. In combination, a pair of relatively rotatable members adapted to be positioned in a bore hole, means for defining the side of one of said members occupying a particular azimuthal position when that member is stationary in the bore hole and for thereafter defining that side during rotation of said member, and means for clutching said members together for simultaneous rotary movement when said defined side of the first member occupies a predetermined angular relationship to the second member.

7. In combination, a pair of relatively rotatable members adapted to be positioned in a bore hole, an element, means for mounting said element for movement to an operative position defining the low side of one of said members when said member is stationary in the bore hole, means effecting rotary movement of said element with said member after the element assumes said operative position, and means on the second member engageable with said element during rotation of the first mentioned member to effect rotation of the second member with the first.

8. In combination, a pair of relatively rotatable members adapted to be positioned in a bore hole, an element, means mounting said element for free movement relatively to one of said members to a position defining the low side thereof, means effecting fixing of said element to said member for rotation therewith, and cooperating means on the second member engageable with said element during rotation of the first mentioned member to effect rotation of the second member with the first.

GEORGE A. SMITH.
